UNITED STATES PATENT OFFICE

2,325,420

REVERSIBLE CURTAIN

Frederick S. Nichols, Melrose, Mass.

Application July 22, 1942, Serial No. 451,813

9 Claims. (Cl. 160—330)

The invention relates to reversible curtains of the type having rod-receiving pockets at both ends so that either end may be used as the top or bottom of a curtain.

It is the primary aim and object of the present invention to provide a curtain of this type whose ends are identically constructed, yet have an altogether different appearance when the curtain hangs, so that an observer will never suspect the reversibility of the curtain.

It is a more specific object of the present invention to provide a curtain of the above type the upper pocket of which shows and the lower pocket of which is completely hidden from view regardless of how the curtain is hung, thereby obliterating all indications that the curtain is reversible.

The foregoing and other objects of the invention, together with means whereby the latter may be carried into effect will best be understood from the following description of an illustrative embodiment shown in the accompanying drawings: in which,

Fig. 1 is a front view of a curtain embodying the present invention;

Fig. 2 is a section taken along the line 2—2 of Fig. 1.

Referring to the drawing, the reference numeral 10 designates the body of a curtain which may be of any suitable material such as lace, for instance. The upper and lower margins or ends 12 of the curtain body are turned back and sewed in place by lines of stitching 14 and 16 to form identical open-ended pockets 18 through either one of which may be passed a curtain rod 20, depending on which end of the curtain is used as the top. Attached to the outer ends of the pockets 18, preferably by the lines of stitching 16, are outwardly projecting ruffles 22 which extend throughout the length of these pockets. Also attached to the curtain body and more particularly to the inner ends of the pockets 18, preferably by the lines of stitching 14, are outwardly projecting ruffles 24 which extend throughout the length of these pockets and preferably continue along one or both side edges of the curtain body.

When the curtain is hung from the curtain rod 20, the lower ruffles 22 and 24 droop or fall naturally as illustrated in Figs. 1 and 2, while the upper ruffles 22 and 24 assume a different relative disposition. Thus, the upper outer ruffle 22 has a natural tendency to remain more or less erect due to the staying action of the curtain rod on the adjacent pleats 26 of this ruffle and the unhindered course of the loose undulations of the

latter to both sides of the curtain body. Hence, even if the upper outer ruffle 22 of the hanging curtain is patted down somewhat by hand, if this is desired, the same will not readily droop beyond the inclination shown in Fig. 2 and will generally not conceal any part of the upper pocket 18 from view. The upper inner ruffle 24 will, on the other hand, generally droop substantially in the manner indicated in Figs. 1 and 2, and not conceal the upper pocket 18, because the undulations of this ruffle are confined to one side of the curtain body and its pleats 28 are not in any way stayed by the curtain rod. The inner ruffles 24 are preferably of larger width than the pockets 18 so that the lower one of these ruffles covers the lower pocket 18 substantially in the manner indicated in Fig. 1.

It is evident that the different appearance of the ruffles 22 and 24 at the top and bottom of the curtain not only conceals the reversibility of the curtain but even strongly suggests that the same is not reversible. This suggestion of no reversibility is even enhanced when the lower inner ruffle 24 completely covers or hides the lower pocket 18 as shown in Fig. 1. Of course, when the curtain is reversed, the ruffles at the top and bottom thereof will of themselves assume the general relative disposition shown in Fig. 1, and any patting of the same by hand, while corrective, will not amount to a reorganization of these ruffles substantially different from that shown in Fig. 1.

While the preceding description had to do with a preferred embodiment of the present invention, it is obvious that numerous modifications suggest themselves which fall fully within the scope of the present invention. For instance, one of the outer ruffles 22 may be dispensed with, in which case the bottom pocket would always be covered by the adjacent inner ruffle and the top and bottom of the curtain would always have a different appearance regardless of how the curtain is hung, thus carrying the deception of the reversible curtain very far. Also, the ruffles which flank the pockets 18 on both sides may project in different directions, since they cause the pockets, if exposed to view, to appear as mere continuations of the curtain body beyond the inner ruffles 24 and thus accomplish the desired deception.

I claim:

1. A curtain having rod-receiving pockets at both ends, and ruffles extending along the top and bottom, respectively, of a pocket substantially throughout the length thereof,

2. A curtain having rod-receiving pockets at both ends, and ruffles projecting from the top and bottom, respectively, of each pocket and extending substantially throughout the length of the latter.

3. A curtain having rod-receiving pockets at both ends, and ruffles projecting outwardly from the top and bottom, respectively, of each pocket and extending substantially throughout the length of the latter.

4. A curtain having rod-receiving pockets at both ends, and ruffles projecting outwardly from the top and bottom, respectively, of each pocket and extending substantially throughout the length of the latter, the inner ruffles being of a width to substantially cover the adjacent pockets, respectively.

5. A curtain comprising a body, rod-receiving pockets at both ends of said body, end ruffles projecting from the top and bottom, respectively, of each pocket and extending substantially throughout the length of the latter, and at least one side ruffle on said body joining an end ruffle at each end of the said body.

6. A curtain comprising a body, rod-receiving pockets at both ends of said body, end ruffles projecting outwardly from the top and bottom, respectively, of each pocket and extending sub-

stantially throughout the length of the latter, and at least one side ruffle on said body projecting outwardly therefrom and joining an end ruffle at each end of said body.

5. A curtain comprising a body, rod-receiving pockets at both ends of said body, end ruffles projecting outwardly from the top and bottom, respectively, of each pocket and extending substantially throughout the length of the latter,
10 the inner ruffles being of a width to substantially cover the adjacent pockets, respectively, and at least one side ruffle on said body joining said inner ruffles.

8. A curtain comprising a body having hems at both ends to serve as rod-receiving pockets, and projecting ruffles attached to the top and bottom, respectively, of each pocket and extending substantially throughout the length of the latter.

15 9. A curtain comprising a body having hems at both ends to serve as rod-receiving pockets, projecting end ruffles attached to the top and bottom, respectively, of each pocket and extending substantially throughout the length of the latter, and at least one side ruffle on said body
20 25 joining the inner ones of said end ruffles.

FREDERICK S. NICHOLS.
